UNITED STATES PATENT OFFICE

OVE L. GAMMELL AND ROLAND W. WOODWARD, OF ATTLEBORO, MASSACHUSETTS, AS
SIGNORS TO SMITH & CROSBY, OF ATTLEBORO, MASSACHUSETTS, A COPARTNERSHIP
COMPOSED OF ALFRED D. CROSBY AND GEORGE H. CROSBY

BRACELET CONSTRUCTION

Application filed April 13, 1929. Serial No. 354,790.

This invention relates to bracelets but more particularly to the extensible type.

One of the objects of the invention is to provide a simple, durable and attractive form of bracelet which may be temporarily enlarged to permit it to be easily slipped over the hand of the wearer and then contracted to fit the arm.

Another object is to provide an effective means for retaining the bracelet in contracted form.

Another object is to provide a simple and readily operated means for releasing the retaining means to permit the bracelet to be removed from the arm. Other objects will be in part obvious and in part pointed out hereinafter.

The invention accordingly consists in the features of construction, combination of elements, arrangement of parts, all as will be hereinlater illustratively described, and the scope of the application of which will be indicated in the following claims.

In the accompanying drawings, in which are shown the features of a selected embodiment of this invention:—

Fig. 1 is a top plan view of a bracelet in contracted position.

Fig. 2 is the same as Fig. 1 except that the parts are in extended position.

Fig. 3 is an enlarged fragmentary plan view, partially in section, the parts being in the position of Fig. 1.

Fig. 4 is a side elevation, partially in section, of the portion of the bracelet shown in Fig. 3.

Figs. 5 and 6 are transverse sections on the lines 5—5 and 6—6 respectively of Fig. 4.

Fig. 7 is an enlarged central longitudinal section of the extensible device as shown in Fig. 2.

Fig. 8 is a top plan view of the device shown in Fig. 7.

Referring to the drawings, the bracelet shown is of the type used with wrist watches and comprises a pair of link sections 10 and 11 connected by an extensible device 12. The ends 13 and 14 are provided with suitable means for engaging the bails on a watch.

The extensible device 12 comprises three

sections or links 15, 16 and 17 which are hingedly connected as at 18 and 19 and to the sections as at 20 and 21. The sections 15 forms a housing for the other two sections when the device is in folded or contracted position. The parts are customarily brought to this position from their extended position by lifting the section 15, carrying it over the section 17 and placing it thereon. This movement causes the section 16 to swing upon its pivots end for end and upon the completion of this movement the sections of the device are nested as shown in Figs. 4 to 6.

In order to effectively retain the parts of the extensible device in folded or contracted position, a latch mechanism has been provided which is automatically engaged when the parts are brought to this position and remains in such engagement until manually disengaged in the manner which will be presently described.

This latch mechanism comprises a spring member 30 which is U shaped and adjacent the free ends thereof and connected thereto are a pair of latch members 31 and 32 in the form of depending lugs bent outwardly at their lower ends as 33 and 34 to engage and interlock with corresponding shoulders 35 and 36 formed on the section 17. These shoulders are preferably abrupt to provide a positive lock when the parts are engaged and thus prevent accidental disengagement of the parts and extension of the bracelet. The member 30 is retained within the housing section by means of bent over flanges 37 and 38 which provide the necessary support without interfering with the action of the member.

In order to be able to manually release the latching mechanism and permit the device 12 to be extended, there are formed laterally projecting arms or lugs 42 and 43 on the corresponding free ends of the member 30. These extend in opposite directions and project through corresponding perforations 44 and 45 in the side walls of the housing section 15. These arms or lugs 42 and 43 must be pressed inwardly or toward each other simultaneously so that both latches are at the same time disengaged or the sections cannot be extended. This is advantageous as it

precludes accidental release by pressure exerted on one or the other of the lugs either by the bracelet coming in contact with some object or by movement of the hand or arm on which the bracelet is worn.

The latch mechanism is extremely easy to release when such is desired. The usual method is to place the thumb on the end of one lug and the first finger on the corresponding portion of the other and press these inwardly simultaneously, then while the latches are thus held released, raise the section 15 and move it endwise away from the section 17. The link 16 during this movement swings end for end about its pivots. As soon as the pressure on the lugs is released the resiliency of the member 30 causes the latches to return to their outer or engaging position in readiness to again engage the shoulders 35 and 36 on the section 17 when the sections are folded. Notches as 46 and 47 may be provided in the ends of the lugs 42 and 48 respectively to facilitate the manual operation.

In the present embodiment the pivot at 19 extends through the side walls of the member 15 and also the bent over flanges 48 and 49, similar in character to the flanges 37 and 38. These flanges 48 and 49 serve to reinforce the corresponding side walls. The pivots at 18, 20 and 21 operate in bearings formed by flanges struck from the metal of the sections of the extensible device.

The latch mechanism as shown acts to positively hold the sections in folded position and accidental release such as frequently occurs with mere frictional holds is rendered well nigh impossible. This mechanism is quickly and easily released by manual pressure and the releasing means cannot be accidentally operated as both latches must be disengaged simultaneously, or in other words, both releasing lugs must be held in their inward position to enable the device to extend or be extended.

It will thus be seen that there is provided a construction of an essentially practical nature in which the several objects of this invention are attained.

As many other embodiments may be made of the features of the above invention without departing from the scope of the invention, it is to be understood that all matter herein set forth or shown in the accompanying drawings is to be interpreted as illustrative and not in a limiting sense.

We claim:

1. In a flexible bracelet, in combination, an extensible device including a plurality of connected sections adapted to fold one upon the other and adapted to move into an unfolded position, spaced latching devices on one section adapted to cooperate with catch devices on another section for retaining said sections in folded position, and means for

simultaneously releasing said latching devices.

2. In a bracelet construction, in combination, an extensible device including a housing and a plurality of sections foldably connected thereto adapted to fold one upon the other within said housing to permit the bracelet to be shortened and adapted to unfold to permit the bracelet to be expanded, spaced latch members on said housing and catch members on one of said sections adapted to interlock to retain said sections in their folded position, and means for simultaneously actuating said latches.

3. In a bracelet construction, in combination, an extensible device including a plurality of connected sections adapted to fold one upon the other to permit the bracelet to be shortened and adapted to unfold to permit the bracelet to be expanded, spaced latch members and catch members on said sections adapted to interlock to retain said sections in their folded position, and spaced members operatively related to said latch members extending from different portions of one section for simultaneously actuating said latches to release said sections from their folded position.

4. In a bracelet construction, in combination, extensible means including a plurality of connected sections foldable one upon the other, a plurality of spaced latch members upon one of said sections adapted to cooperate with a plurality of catches on another of said sections to hold said sections in their folded position, and means for simultaneously releasing said latches from said catches to permit said sections to be unfolded.

5. In a bracelet construction, in combination, a housing link, a plurality of sections hingedly connected thereto and adapted to fold into position upon said housing link, a spring in said housing carrying latches thereon, said latches adapted to catch on one of said sections to hold said sections in their folded position, and means for simultaneously releasing said latches from said sections.

6. An extensible device for a bracelet comprising a plurality of sections connected substantially end to end and adapted to be folded one on the other, one of said sections forming a housing for the other sections when the device is in folded position, and latch mechanism for temporarily retaining the device in said position including a substantially flat spring member within said housing section having lugs thereon interlocking with corresponding shoulders on another of the sections.

7. An extensible device for a bracelet comprising a plurality of sections hingedly connected to be folded one upon the other with one of said sections forming a housing for the other sections, means for temporarily retaining the device in folded position includ-

- ing latch members mounted on the housing section and engaging corresponding shoulders on one of the other sections, and means for manually moving said latch members to disengage said shoulders and release said sections. 8. An extensible device for a bracelet comprising a plurality of connected nesting members one of which forms a housing for the other members when said members are in nested position, means for retaining the members in said position including a pair of spring pressed latch members mounted within said housing member and engaging corresponding shoulders on one of the other members, and means projecting from said housing and connected to said latch members to enable said latch members to be manually disengaged. 9. An extensible device for a bracelet comprising a plurality of connected nesting members one of which forms a housing for the other members when said members are in nested position, means for retaining the members in said position including a pair of spring pressed latch members mounted within said housing member and engaging corresponding shoulders on one of the other members, and arms projecting from said latch members through said housing to enable the latch members to be manually disengaged. 10. An extensible device for a bracelet comprising a plurality of connected nesting members one of which forms a housing for the other members when said members are in nested position, means for retaining the members in said position including a substantially U shaped spring member mounted in said housing member and having upon its free ends latches engaging corresponding shoulders on one of the other nesting members, and lugs formed on said spring member and projecting through the corresponding sides of the housing member, said lugs being adapted to be manually pressed to disengage the latches and release said nesting members. 11. In a bracelet construction, in combination, a housing link, a plurality of sections hingedly connected thereto and adapted to fold into position upon said housing link, a spring in said housing carrying latches thereon, said latches adapted to catch on one of said sections to hold said sections in their folded position, and members operatively related to said spring extending through said housing adapted to release said latches from said catches. 12. In a bracelet construction, in combination, a housing link, a plurality of sections hingedly connected thereto and adapted to fold into position upon said housing link, a spring in said housing carrying latches thereon, said latches adapted to catch on one of said sections to hold said sections in their folded position, and lugs operatively related to said latches extending through the opposite walls of said housing and adapted to release said latches upon application of pressure thereto. 13. In flexible bracelet construction, in combination, an extensible device including a plurality of connected sections adapted to fold one upon the other and adapted to be unfolded, spaced latching devices on one section adapted to cooperate with catch devices on another section for retaining said sections in folded position, and spaced members operatively related to said latching devices for simultaneously actuating said latching devices to release said sections from their folded position. In testimony whereof, we have signed our names to this specification this tenth day of April, 1929.
